BAR STOOL

Leopold Durko, Morton Grove, Ill., assignor to Comfort Lines, Inc., Chicago, Ill.

Filed Apr. 22, 1965, Ser. No. 84,917

Term of patent 14 years

(Cl. D15—8)

The dominant features of my design reside in the portions shown in full lines.

I claim:

The ornamental design for a bar stool, substantially as shown and described.
